UNITED STATES PATENT OFFICE.

JAMES O. RICHARDSON, OF BOSTON, MASSACHUSETTS.

STEAM-TRAP.

SPECIFICATION forming part of Letters Patent No. 425,108, dated April 8, 1890.

Application filed February 10, 1890. Serial No. 339,892. (No model.)

To all whom it may concern:

Be it known that I, JAMES O. RICHARDSON, of Boston, in the county of Suffolk and State of Massachusetts, have invented certain new 5 and useful Improvements in Steam-Traps, of which the following, taken in connection with the accompanying drawings, is a specification.

The object of my invention is to so improve the construction and arrangement of the 10 parts of a steam-trap that it shall work very promptly upon a slight accumulation of water and be cheap and durable. This object I attain by the mechanism shown in the accompanying drawings, in which—

15 Figure 1 is a vertical longitudinal section. Fig. 2 is a cross-vertical section taken on line $x-x$ of Fig. 1. Fig. 3 is a vertical section through the valve-tube, showing the valve open.

20 In the drawings, A represents the water and float chamber case, and is provided at one end with a hand-hole device A', for convenience in cleaning and repairing, and an inlet-pipe A².

B is a valve-tube attached by screw-threads 25 or otherwise to the case A and by a union-coupling D to the discharge or waste pipe C, which, if desired, may be connected to a water-tank. (Not shown.) The valve E swings on a horizontal pivot P and is connected to a

30 rod H, said rod H having at its end a float K. The extension H' of the rod H serves as a lever against which the screw S may be operated when it is desired to force the valve E open, as indicated in dotted lines. The 35 valve E is so fitted to the valve-tube B that when it stands in its normal position no flow of steam or water can take place in the valve-tube B; but when inclined, as indicated by dotted lines, then steam or water, as the case

40 may be, can freely flow around the edges of the valve through the grooves F F, made in the interior of the water-tube. The valve E is pivoted upon the pin P, which passes through the walls of the valve-tube and centrally through the valve, as shown. When 45 the pin P is in place, the ends are entirely

covered by the union-coupling D and held in place.

By making the case A and its inlet A² and valve-tube B in the manner shown, I have a 50 clear working-passage from the inlet to the outlet, so that it is a very simple matter to clear out the trap when it becomes foul.

My valve operates as follows: If there is no water in the chamber of the trap, then the 55 float K will lie on the bottom of the chamber and the valve E will remain in its normal position—that is, closed,—and no water can escape; but if water accumulates in the chamber then the float K will rise up, as indicated 60 in dotted lines, and the valve E will open (see Fig. 3) and allow a free passage of water over and under it through the grooves F F. As the water escapes the float will lower and close the valve, and so hold it until the water 65 again accumulates.

I claim—

1. In a steam-trap, the combination of a chamber having an inlet and outlet passage aligned with each other and with the trend 70 of the said chamber, with a valve adapted to close and open said outlet-passage and an operating-float attached to said valve, all operating together substantially as and for the purpose set forth.

2. In a steam-trap, the combination of a valve-tube having grooves F F with a valve E and float K, substantially as and for the purpose set forth.

3. In a steam-trap, the combination of the 80 valve-tube B, the union-coupling D, the pivot-pin P, held in place by the said union-coupling, and the valve E, substantially as and for the purpose set forth.

In testimony whereof I have signed my 85 name to this specification, in the presence of two subscribing witnesses, on this 6th day of February, A. D. 1890.

JAMES O. RICHARDSON.

Witnesses:

FRANK G. PARKER,
WM. R. WIGGIN.
